UNITED STATES PATENT OFFICE.

THOMAS W. HOLLEY, OF RANGER, TEXAS.

SAND-REEL PEDESTAL AND CONTROL MECHANISM.

Application filed February 10, 1921. Serial No. 444,030.

To all whom it may concern:

Be it known that I, THOMAS W. HOLLEY, a citizen of the United States, residing at Ranger, in the county of Eastland and State of Texas, have invented certain new and useful Improvements in Sand-Reel Pedestals and Control Mechanism, of which the following is a specification.

My present invention relates to well drilling rigs and more particularly to pedestal and control mechanism for the sand reels thereof used in the lowering and drawing of sand pumps or bailers.

It is now common practice to support the sand reel by a shaft received at one end by a tail post and at its other end by lever carried by knuckle post, the lever being manually actuated by a sand reel handle and reach connecting the handle and lever. The use of this arrangement results in notching or cutting of a gain in main sill for fastening of the knuckle post thereto materially weakening the sill. The lever, usually made of wood receives the end of the sand reel shaft by a hole bored in the lever and which becomes rapidly enlarged making necessary replacement which takes time and is a considerable expense when replacement is frequently required. In the erection of well drilling rigs it is the usual practice to frame the timber on the ground where erection is to take place and the erection and adjustment of this portion of the rig,—relating to the sand reel takes considerable time and labor.

One of the principal objects of the present invention is to provide a pedestal and control for sand reels which may be quickly and securely placed and adjusted with respect to the main sill and usual band wheel of the rig to be operated thereby.

Another object of the invention is to provide a pedestal and control mechanism which is durable, the end of the sand reel being received in a bearing block adapted to receive a lining of alloy metal, such as Babbitt metal, readily replaced and capable of being remelted and reused.

A further object of the invention is to provide a pedestal which may be mounted upon and connected with the main sill of the rig without multilation of the latter.

Other objects and advantages of the invention will appear in the following detailed description taken in connection with

the accompanying drawings, forming a part of this specification, in which drawings:

Figure 1 is a side elevation of a portion of well drilling rig showing a pedestal and reel control mechanism, constructed according to the principle of my invention, applied thereto.

Fig. 2 is a plan view of the sand reel portion of the rig.

Fig. 3 is a detail view partly in elevation and partly in vertical section of the pedestal and a portion of the control mechanism.

Fig. 4 is an enlarged sectional view on the line 4—4 of Fig. 1 of the drawings.

In the drawings, where similar characters refer to similar parts throughout the views, A designates the main sill, B the sub sill, C the sand reel tail sill and D the mud sills of the rig; E the sand reel, F and G its shaft and pulley respectively; H the band wheel for engagement with pulley G; and J the derrick floor all of which may be of the usual or any preferred construction. The one end of shaft F may be supported by a tail post or pedestal of the usual construction but in the example shown is supported by a pedestal K of the character disclosed in my co-pending application for patent filed on the tenth day of February, 1921, Serial Number 444,029. The present invention is designated by L as to the pedestal and M as to control mechanism for the reel.

The invention is herein shown as applied to what is commonly known as the standard rig, in which the sand reel shaft F is disposed with its axis extending diagonally cross wise the plane of band wheel H, but it is to be understood that the principle of this invention may be applied to other types of rig, without departing from the spirit of the invention. It is understood that, in practice, the sand reel E is used for the purpose of lowering and raising a sand pump or brazier, not shown in the drawings, as by use of a cable 5, and this is accomplished by moving the shaft F so that the pulley G is moved into and out of engagement with the band wheel H.

The particular type of pedestal or tail post K, shown in Figure 2 of the drawings does not form a part of the present invention, but is more specifically disclosed in my co-pending application for patent hereinbefore referred to. It is shown merely by way of example to indicate that the shaft

F, when moved, for bringing the pulley G into and out of engagement with the band wheel H, pivots in bearing 6 of the pedestal K.

5 The pedestal L comprises, broadly, a base 7, a frame 8, and a bearing block 9 slidable in frame 8. The base 7 has means 10 for securing the base to the main sill A of the rig, so that it may be adjusted longitudinally of the sill, or in other words, in a plane parallel to the plane of band wheel H. The frame 8 has means 11 for securing it to the base 7 and permitting adjustment of the frame toward or from the plane of the band wheel H.

The base 7 in the example shown comprises a pair of base bars 12 arranged in parallel spaced apart relation, and a connection 13, such as a piece of timber which 20 is secured to the under side of the bars 12, and which may be secured to the bars in any suitable manner, such as by bolts 14 and nuts 15. The base bars 12 are preferably formed of rolled angle section, thus providing a 25 horizontally disposed flange 16, and vertically disposed flanges 17. For a purpose to be subsequently set forth there is provided adjacent each end of flange 16, a perforation 18, and the vertical flanges 17 are each 30 provided with a series of perforations 19 arranged longitudinally of the flange. The base 7 may also comprise one or more filler pieces 20, which may be interposed between the connection 13 and the base sill A in 35 order to dispose the base bars 12 at the desired distance above the upper face of the main sill, these filler pieces being preferably arranged directly beneath the base bars, as clearly shown in Figure 1 of the drawings.

The means 10 for securing the base to the main sill may comprise clamp bars 21 adapted to engage the under side of sill A, and take up devices 22, which latter may each 45 be in the form of a rod 23 screw threaded at opposite end portions, and nuts 24 in screw threaded engagement with these end portions. Each clamp bar is provided adjacent its end portions with perforations 25, there 50 being one clamp bar for each base bar, the perforations 25 being aligned with the perforations 18 in the base bar. The rods 23 are thus accommodated in the perforations 18 and 25, and by turning the nuts 24 tight, 55 the base 7 may be secured to the base sill against longitudinal and lateral movement with respect thereto. The base may be adjusted, however, longitudinally of the sill, as is obvious from the foregoing, it being 60 necessary to merely release some of the nuts 24 and shift the base 7 longitudinally of the sill.

The frame 8, in the example shown, comprises a pair of uprights 26, in spaced apart 65 relation, and horizontal guide members 27

secured to the uprights 26 in spaced apart relation. The uprights 26 may be conveniently formed from rolled channel sections, one of which is provided with a vertical slot or opening 28 for a purpose to be subsequently set forth. The guide members 27 may be substantially H shaped in cross section, whereby each member is provided with parallel flanges 29, serving to hold the bearing block 9 against movement laterally of 75 the frame. The guide members may be secured to the uprights, in any suitable manner, such as by bolts and nuts 30 and 31, respectively.

Referring now to the means 11 for securing the frame 8 to the base 7, permitting adjustment of the frame toward or from the plane of the band wheel H, such may consist merely of bolts 32 and nuts 33, although it is desirable to also provide braces 34, connected to the upper portion of the frame as by one of the bolts 30 and nuts 31, and to the base bars as by bolt 34' and nut 35, these braces acting as struts, since most of the pressure incident to operation of the sand reel, is outwardly, the bearing block 9 acting somewhat as a thrust bearing where a beveled pulley G is used. The shanks of bolts 32 may be extended through any selected 85 perforations 19, these perforations permitting of adjustment of the frame 8 toward or from the plane of the band wheel H.

Bearing block 9 may be formed of a single piece of metal, or may be built up in any suitable manner, it sufficing to show, 100 in the example shown, that the block is provided with an opening 36 for the reception of shaft F, a lining of Babbitt metal or its equivalent 37, being provided in said opening, and the block also having grooves 38 105 at its upper and lower faces for the reception of the flanges 29. While but slight movement of the block is necessary to bring the pulley G into and out of engagement with the band wheel H, the frame 8 is made 110 relatively long so that it is possible to move the bearing block 9 a considerable distance in either direction, before it will engage either uprights 26. This has a material advantage as will be noted hereinafter, since 115 it is not always possible to clamp the base 7 to the main sill in a manner that the shaft E is accurately positioned for engagement of the pulley G with the band wheel H, by operation of the mechanism M.

The mechanism M comprises, an arm 40 extending from one end of frame 8; a lever 41 in the example shown, pendently supported by arm 40; a link 42 connecting bearing block 9 and lever 41; an arm 43 125 extending from base 7 in the same direction as arm 40; a lever 44 pivotally connected to arm 43 at one end and to lever 41 intermediate its ends; a sand reel lever 45 on platform J adapted to be manually 130

actuated; and a reach 46 operatively connecting levers 44 and 45, so that when movement is imparted to lever 45 it will be transmitted through reach 46, lever 44, lever 41 and link 42, to the bearing block 9. It is preferred to provide the arm 40 with a plurality of perforations 47 longitudinally thereof, and to provide a plurality of perforations 48 in spaced apart relation longitudinally of lever 41. Also link 42, may be provided with a plurality of perforations 49, so that the connecting device 50, such as a bolt, which pivotally connects the lever 41 to arm 40 may be disposed in any of the perforations 47 and 48 selected, for adjustment. Likewise connecting device 51 for the link 42 and lever 41 may be passed through any of the selected perforations 48 and 49, for adjusting purposes, as herein-after noted. The arm 43 and lever 44 is provided mainly to permit of disposing the sand reel operating lever 45 in the belt house or well within the margins of the platform J, and so as to avoid engagement of the reach 46 with a standard 52 of the band wheel H, which is usually a stock feature. The connection between lever 44 and arm 43 may be by means of a pin or bolt 53 extending through an elongated slot 54 in the end portion of lever 44. The reach 46 may be made up of a plurality of sections detachably and adjustably connected, as indicated at 55, and the end portion of the reach adjacent lever 45 may be provided with a plurality of perforations 56 any one of which may be aligned with any one of a plurality of perforations 57 in lever 45, a bolt 58 serving to pivotally connect the lever with the reach.

It is to be noted that the perforations 47, 48 and 49 permit a wide range of adjustment as to the relative position between the bearing block 9 and the operating lever 45. The relatively long guide bars 27 enable the workmen to quickly assemble the pedestal into operative relation to the main sill by use of means 10, accurate adjustment at such time not being necessary. When assembling the shaft into operative relation with the bearing block 9, the entire frame 8 may be moved toward or from the complementary pedestal K, according to the length of the shaft to be accommodated, this being possible because of the provision of means 11. After the mechanism has thus been assembled it is desirable to adjust the mechanism so that the pulley G will have good frictional contact with the band wheel H, so as to not wear the latter. This may be accomplished by either adjusting the pedestal K, or by adjustment of the mechanism M. The link 42 extends through the opening 28 in upright 26, which opening is of sufficient size

to permit the link to swing incident to movement of lever 41. 65

Changes in details may be made without departing from the spirit or scope of my invention; but,

I claim:

1. A pedestal for sand reel comprising in combination, a pair of base bars arranged in parallel spaced apart relation and each having a longitudinally and a vertically disposed flange, said horizontal flanges provided with perforations adjacent their ends and said vertical flanges each provided with a series of perforations arranged longitudinally of the flange, a clamp bar for each base bar, said clamp bars provided with perforations aligned with said perforations in the horizontal flanges of said base bars, adjustable take up devices accommodated in the said aligned perforations of said clamp bars and base bars for clamping the base bars to the main sill of the rig, a bearing block, a frame receiving and guiding said bearing block and permitting movement thereof longitudinally of the frame, and means securing said frame to said base bars 85 in adjusted position longitudinally thereof, said means including elements passing through selected perforations in said vertical flanges of said base bars.

2. A pedestal for sand reels comprising in combination, a pair of base bars arranged in parallel spaced apart relation and each having a horizontally and a vertically disposed flange, said vertical flanges each provided with a series of perforations arranged longitudinally of the flange, a clamp bar for each base bar, adjustable take up devices operatively connecting said clamp bars and base bars to permit clamping of the latter to the sill of a drilling rig, a bearing block, a frame receiving and guiding said bearing block and permitting movement thereof longitudinally of the frame, means for securing said frame to said base bars in adjusted position longitudinally thereof, said means including elements passing through selected perforations in said vertical flanges of said base bars. 105

3. A pedestal for sand reels comprising in combination, a pair of base bars arranged in parallel spaced apart relation and each provided with a series of perforations arranged longitudinally thereof, means for securing said base bars to the sill of a drilling rig, a bearing block, a frame receiving and guiding said bearing block and permitting movement thereof longitudinally of the frame, and means for securing said frame to said base bars in adjusted position longitudinally thereof, said means including elements passing through selected perforations in said base bars. 115 120 125

THOMAS W. HOLLEY.
